UNITED STATES PATENT OFFICE.

WALTER T. RAYMOND, OF ST. LOUIS, MISSOURI.

TICKET FOR USE IN MERCHANTISING CAMPAIGNS.

Application filed October 12, 1923. Serial No. 668,214.

To all whom it may concern:

Be it known that I, WALTER T. RAYMOND, a citizen of the United States, residing at St. Louis, Missouri, have invented a certain new and useful Improvement in Tickets for Use in Merchandising Campaigns, of which the following is a full, clear, and exact description, such as will enable others skilled in the art to which it appertains to make and use the same.

This invention relates to devices that are used in merchandising campaigns of the kind where a premium or prize is given by a merchant or manufacturer to one of a large number of purchasers of merchandise.

The main object of my invention is to eliminate the possibility of a particular user obtaining the premium in a merchandising campaign of the kind referred to through dishonesty or collusion between said purchaser and the merchant or manufacturer who offers the premium.

To this end I propose to issue a ticket or check to each purchaser that contains the representation of a clock face or numbers or words which denote a certain fraction of time, and use a clock to determine which purchaser is entitled to the premium.

Figure 1 of the drawings illustrates the form of ticket or check that I prefer to use.

Figure 2 illustrates a clock that is used in conjunction with said tickets; and

Figure 3 illustrates another form of ticket that may be used.

In carrying on a merchandising campaign with my improved apparatus a clock A, preferably an eight-day clock, is set in operation, and thereafter, each person who makes a purchase at the store where the campaign is in progress is given a ticket or check B which contains indicia that represents a certain fraction of time. The indicia on the various tickets B represent different fractions of time and there are no duplicate tickets. Usually the complete set or group of tickets will comprise 1440 tickets, as there are 1440 minutes in a day and the tickets will be differentiated from each other by fractions of one minute. For example, if tickets of the kind shown in Figure 1 are used each ticket will have printed thereon a clock dial 1, a minute hand 2, and an hour hand 3, the hands of the various tickets being positioned at va-

rious points on the dials. I prefer to connect the tickets together so as to form a long ticket strip that is divided into sections by transverse rows of perforations 4 and print the clock face on the tickets in such a way that the position of the minute hand on the dial distinguishes a particular ticket from the immediately preceding and the immediately succeeding ticket. Thus, as shown in Figure 1, the first ticket of the strip will represent five minutes past five; the second ticket will represent six minutes past five; the third seven minutes past five, etc.

The tickets are issued to the persons who make purchases while the campaign is in progress and when the clock A runs down and stops, the holder of the ticket which represents the minute and hour that the clock stopped is entitled to the premium. As it is impossible to tell the exact minute that the clock will stop, each purchaser has an equal chance of winning the premium.

Instead of connecting the tickets together so as to form a long ticket strip, the tickets can be formed by separate pieces of cardboard or other suitable material that are not connected together. Furthermore, while I prefer to use tickets that have clock faces printed on same, it is obvious that the same result could be obtained by words or numbers printed on the tickets, as shown in Figure 3.

Having thus described my invention, what I claim as new and desire to secure by Letters Patent is:

1. A group of checks for the purpose described, each of which is provided with a representation of a clock face, and clock hands, the clock hands of the different checks being disposed differently so as to represent different fractions of time.

2. A group of tickets for the purpose described, each of which is provided with a representation of a clock face, said tickets being distinguished from each other by fractions of one minute.

3. A ticket strip of the character described divided into a number of sections, each of which contains a clock dial and a minute and an hour hand, the hands of the various tickets being differently arranged so that no two tickets represent the same fraction of time.

WALTER T. RAYMOND.
